UNITED STATES PATENT OFFICE.

CHARLES G. PERKINS, OF NEW YORK, N. Y., ASSIGNOR TO THE IMPERIAL ELECTRIC LIGHT COMPANY, OF SAME PLACE.

CONDUIT FOR ELECTRICAL CONDUCTORS.

SPECIFICATION forming part of Letters Patent No. 319,998, dated June 16, 1885.

Application filed January 16, 1884. (No model.)

To all whom it may concern:

Be it known that I, CHARLES G. PERKINS, a citizen of the United States, and a resident of New York, in the county of New York and State of New York, have invented certain new and useful Improvements in Conduits for Electrical Conductors, of which the following is a specification.

My invention relates to conduits for electrical conductors designed for attachment to walls and ceilings.

In that form of my invention which is designed to be applied to ceilings I use a strip of wood or other insulating material, which I call the "carrier - strip," and on opposite sides of which are cut grooves made on converging lines. The grooves are so cut as to slope downward when the carrier-strips are in position. Conducting-wires of an electric circuit or circuits are placed in the grooves, and over the wires are placed small strips of insulating material, which I call "groove-strips." These strips are made to fit the grooves, though it is not necessary that they should fit tightly, inasmuch as, owing to the position of the conducting-wires and groove-strips when the carrier-strip is secured in place, their own weight tends to hold them without displacement.

In that form of my invention which is designed to be applied to walls parallel grooves sloping downward are made on the same side of the carrier-strip. The wires and groove-strips are held in position by gravity, as before.

In the drawings, Figure 1 represents a cross-section through *xx* in Fig. 2 of my improved device as applied to a ceiling. Fig. 2 represents a side elevation of the same. Fig. 3 is a cross-section through *yy* in Fig. 4 of my improved device as applied to a wall, and Fig. 4 is a side elevation of the same.

Similar letters refer to similar parts throughout the drawings, in which *a*, Figs. 1 and 2, represents the strip of insulating material called the "carrier-strip;" *b*, the upper plane surface thereof adapted to abut against the surface of a ceiling. *cc* are the converging grooves. *dd* are the electrical conductors held in the grooves *cc* by the groove-strips

e e. *f* in Figs. 3 and 4 is also a strip of insulating material, provided with grooves *g*, one above the other, both arranged on the side opposite the surface abutting against the wall when attached. *h* are the electrical conductors, which are held in the grooves *g* by means of the inclosing groove-strips *i*.

The construction as shown in Figs. 3 and 4 is adapted to be fastened to walls. In this construction the groove-strips may be dispensed with, if desired, as the conductors will be held in position by their own weight.

It will be understood that the strip of insulating material *a* is first loosely attached to walls or ceilings by means of screws in a manner that will allow the abutting surface thereof to remain free from the wall until the electrical conductors *d* and the groove-strips *ee* are properly inserted in the grooves *cc*, after which the strip *a* is fastened tightly to the surface of the wall or ceiling, and the inclosing-strips *ee* are thereby secured in position.

I am aware that strips of insulating material provided with grooves for the reception of electrical conductors which were held in position by strips having a projection on each side thereof, said projections engaging with corresponding grooves on the main strip, have been used.

The conduits heretofore used lack the advantage which I obtain from my method of construction, in that with my method the wires or conductors can be removed, replaced, repaired, or examined without removing the conduit from the wall or ceiling. The old methods are objectionable, because the conductors have to be placed in the grooves before the whole can be attached to a wall or ceiling. These objections are obviated by my invention, which I have fully described.

What I claim as new, and desire to secure by Letters Patent, is--

1. A conduit for electrical wires, consisting of a strip of insulating material provided with a groove or grooves, downwardly inclined and filling strips therefor, whereby the weight of the wires and of the strips retains them in place, and fastening devices therefor are avoided, as set forth.

2. The combination, with a strip of insu-

lating material provided with downwardly-inclined grooves, of electrical conductors and insulating groove-strips, the conductors and groove-strips being adapted to be held in position by their own weight, substantially as shown and described.

Signed at New York, in the county of New

York and State of New York this 12th day of January, A. D. 1884.

CHARLES G. PERKINS.
